UNITED STATES PATENT OFFICE.

ISAAC ST. CLAIR GOLDMAN, OF LOS ANGELES, CALIFORNIA, ASSIGNOR OF ONE-HALF TO
L. S. HACKNEY, OF ST. PAUL, MINNESOTA.

LOCK.

Specification of Letters Patent.

Patented July 6, 1909.

Application filed July 24, 1908. Serial No. 445,116.

No. 927,139.

To all whom it may concern:

Be it known that I, ISAAC ST. CLAIR GOLDMAN, of Los Angeles, Los Angeles county, California, have invented certain new and useful Improvements in Locks, of which the following is a specification.

The object of my invention, is to provide a lock which cannot be successfully tampered with or picked without breaking the lock. A further object is to provide a lock of compact construction having a comparatively small slot or opening for the insertion of a key and thus protecting the lock against the insertion of an explosive or the entrance 15 of dirt or moisture.

A further object, is to provide a lock capable of use with a latch or bolt and with right hand or left hand doors. A further object, is to provide a lock using an improved form of key made of comparatively light and thin material, and to which the force exerted in operating the lock, is applied lengthwise on the key to move it edge 20 lengthwise, instead of laterally with a twisting and strain as usual in locks of this type.

Other objects of the invention will appear from the following detailed description.

The invention consists generally in various constructions and combinations, all as hereinafter described, and particularly pointed out in the claims.

In the accompanying drawings forming part of this specification, Figure 1, is a sectional view illustrating the mechanism of the lock in its normal locked position. Fig. 2, is a sectional view on the line $x-x$ of Fig. 1. Fig. 3, is a view corresponding to Fig. 1, showing the mechanism in its unlocked position. Fig. 4, is a sectional view on the line $y-y$ of Fig. 3, showing the position of the key in the lock. Fig. 5, is a detailed view of the key used with the lock. Fig. 6, is a view illustrating removable points for the key.

In the drawing, 2 represents the casing of the lock having a removable plate 3 through which access may be had to the lock mechanism. 4 is a latch bolt having arms 5 thereon between which a recess 6 is formed to receive a hub 8 that is secured on the knob spindle 9. The arms 5 are provided with heads 10 thereon, that are held in engagement with pins 11 on a plate 12 by means of the tension of a spring 13 that is mounted in said casing and has one end adapted to bear on said latch and normally hold it in its projected position.

The plate 12 has an elongated opening 14 therein to receive the hub 8, and slide thereon during the operation of retracting or projecting the bolt. Guides 15 are provided in the wall of the casing between which the plate 12 is slidable. The pins 11 are in position to be engaged by arms 16 mounted on said hub for the purpose of retracting the bolt when the knob spindle is turned, suitable knobs 17 being provided on each end of the spindle for convenience of operation. The plate 12 has a recess 18 in one end and stops 19 on each side of said recess, formed by turning up the end of the plate.

A series of wards 20 are pivoted at one end in bearings 21 in the wall of the casing and have opposite ends which are adapted to enter the recess 18 when the wards are moved into alignment therewith. At other times, the wards are in the path of one of the stops 19, and positively prevent the retraction of the plate 12 and the withdrawal of the bolt. The wards are normally held in the path of the stop 19 by means of a series of springs 22 which are fastened at one end to the wards 20 and bear at their opposite ends on a post 23. These springs are all independent of one another, and each ward is capable of movement independently of all the other wards. The wards have recesses 24 in one edge which are held in contact with a wall 25 by the tension of the springs 22. This wall has a key hole slot 25' into which the key 26 is inserted. The key has a series of projections or points 27 corresponding in number to the wards. The projections vary in length according to the depth of the recesses in the wards, and are adapted to enter the wards when the key is operated. The projections or points will engage the wards with a direct end pressure and there will be no side twist or strain on them in the operation of the key. I am thus able to make the key shank and the points of comparatively light thin material and provide a correspondingly narrow slot 25 in the lock casing to receive them. This narrow slot will make it practically impossible to insert a tool or any foreign substance into the lock. The key also has a bar 28 adapted to slide in a guide 29 on the key and having a beveled forward end 30 that is adapted to engage the wall at one end of the key hole slot, and force the projections 27 through the holes 27' into engagement with the wards to oscillate them and adjust them

in line with the recess in the plate 12. The bar 28 has a head 31 at one end for convenience in forcing the bar inwardly and pressing the key against the wards.

It will be noted, that the number of projections on the key must correspond to the number of wards and that as each ward is independent of all the others, it will be necessary to operate all of them simultaneously to release the latch bolt. Any variation or inaccuracy therefore, in the length of the projections 27 resulting in a failure to move a ward when the key is operated, will prevent the retraction of the bolt. The wards 15 must be exactly in line at the instant the bolt is thrown and it will be impossible to insert a sufficient number of wires into the key hole opening to hold the several wards in their proper position and allow the bolt to be 20 thrown. It will also be impossible to hold the wards in position to release the bolt without the use of a perfectly formed key and as each ward is independent of all the others, it will not be possible to jar or twist them to 25 adjust them in line to release the bolt. The wards are so situated that they form a brace directly back of the latch bolt, and they also cover the holes communicating with the key slot, thus preventing anything like moisture 30 or an explosive from entering the lock chamber. A post 32 having a knob 33, is mounted in the casing and is provided with a wing 34 which when the post is revolved, is adapted to engage an inclined surface 35 on 35 the wards and force them away from the holes 27' and into alignment with the recess 18 in the end of the plate 12. As long as the wing 34 is in the position illustrated in Fig. 3, the wards will be locked open and the latch 40 bolt be free to slide back and forth. In Fig. 4, I have illustrated a series of removable 45 points 28' to permit the combination of a high grade lock to be changed in case a key is lost or stolen. These points may be removed from the key and others of different length substituted therefor. I am thus able to change the combination of the lock and render the invention applicable to high grade locks such as are used on safes and vaults.

50 A lock for ordinary purposes can be made with a single rigid bolt or with a reversible latch as shown in the drawings. I have illustrated the invention applied to a latch bolt, but it may be used in connection with 55 an independent lock bolt if preferred.

I claim as my invention:—

1. In a lock, a series of pivoted wards, a casing inclosing said wards and having a slot to receive a key, the wall of said slot having a 60 series of holes therein, a key having a series of points adapted to enter said holes and means for forcing said points endwise through said holes into contact with said wards, substantially as described.

65 2. A lock, comprising a casing, a series of

wards arranged therein, each ward being movable independently of all the other wards, said casing having a slot to receive a key the wall of said slot having a series of holes therein, a key having points to enter said holes and means for forcing said key and points into contact with said wards to actuate the same, substantially as described.

70 3. A casing, having a series of wards pivoted therein, each one movable independently of the others, a wall having a series of holes corresponding in number to said wards and opposite the same respectively, a key having points adapted to enter said holes and engage said wards, means for forcing said key edgewise into engagement with said wards and a latch bolt having a recess to receive said wards, substantially as described.

75 4. A lock, comprising a casing, a bolt therefor, a series of wards normally in the path of said bolt and preventing movement of the same, said wards having recesses in one edge and varying in depth, said casing having a slot to receive a key and a key having a series of points of different length 80 adapted to engage the edges of said wards in the recesses therein and means for moving said key laterally to cause its edge to engage and actuate all of said wards simultaneously.

85 5. A lock having a key provided on one edge with a series of points of varying length and a blade slidably mounted on the other edge of said key and having a beveled outer end the engagement of said end with a fixed object causing the lateral movement of said key and endwise movement of the said points.

90 6. The combination, with a lock casing having a slot to receive a key and a wall provided with a series of holes therein, of a key composed of comparatively thin material adapted to enter said slot and having a series of points formed on one edge, said points being adapted to enter the holes in said wall, a slide carried by said key and adapted to engage the wall of said slot and force said points into said holes and a series of wards having their edges in contact with said wall and normally concealing the holes therein.

95 105 110 115 7. A lock, comprising a casing having a slot to receive a key and a wall provided with a series of holes, of wards having edges to contact with said wall and cover said holes, said wards being movable independently of one another and spring devices for holding said wards in engagement with said wall.

120 125 8. A lock, comprising a casing, a sliding bolt therein, a series of wards movable independently of one another, a key having points to contact with said wards and means for moving said key laterally to actuate said wards.

130 9. A lock, having an opening to receive a key and a series of holes in the wall inclosing said opening, a series of wards movable inde-

pendently of one another and yieldingly held against said wall, the edges of said wards closing the holes in said wall, a key having a series of interchangeable points on one edge 5 adapted to enter the holes in said wall, and means for forcing said points into said holes and into engagement with said wards.

10. A lock, comprising a casing, a sliding bolt therefor, a series of wards pivotally arranged within said casing and normally preventing movement of said bolt, said casing having an opening to receive a key, and a wall with holes therein which are normally closed by said wards, and a key having 15 means to enter said holes and actuate said wards.

11. A lock having a sliding bolt and a se-

ries of wards normally preventing movement of said bolt, a key fitting said lock and having points to contact with said wards respectively and means for moving said key in a direction at right angles substantially to its longitudinal axis, substantially as described. 20

12. A lock comprising a casing, a bolt therefor, a series of wards, a wall having 25 holes therein normally closed by said wards, and a key having points adapted to enter the holes in said wall and actuate said wards.

In witness whereof, I have hereunto set my hand this 9th day of July 1908.

ISAAC ST. CLAIR GOLDMAN.
